GAS TUBE WITH REDUCED NOISE

Arthur L. Tirico, Belleville, N. J., assignor to
Radio Corporation of America, a corporation
of Delaware

Application April 2, 1951, Serial No. 218,744

12 Claims. (Cl. 313—71)

1

This invention relates to the reduction of noise in gas tubes and preferably in gas tubes which are suitable for use as amplifiers because they have continuous grid control. More particularly, it relates to the reduction of noise in amplifier gas tubes of a particular kind having very high values of transconductance and of anode current and extremely low values of output impedance which are described in the copending applications having Serial Numbers 185,745, 185,746, now Patent Number 2,588,065, and 217,912, now Patent Number 2,611,884, which were respectively filed on September 20, 1950, September 20, 1950, and March 28, 1951, and all of which were assigned to the same assignee as the present application, and to novel circuits for reducing noise in gas tubes.

Tubes of the particular kind alluded to above, which are referred to as "plasmatrons," have offered very great advantages over gas tubes which preceded them. However, like many other kinds of gas tubes they have the limitation of being somewhat prone to generate spurious noise. In order best to explain this limitation the basic operating principles of the plasmatron will first be reviewed. In this kind of tube there are 20 separate discharge paths for the load current and the ionizing current. The energizing potential required for drawing the former, the load current, from a main cathode to a main anode, is set at well below the value required to produce ionization. However, a higher potential is used to produce a separate ionizing or "auxiliary" discharge. It ionizes the tube's gaseous filling 30 converting it into a conductive "plasma" consisting of positive ions and detached, free negative electrons. The plasma (1) surrounds the main cathode and (2) fills the load current discharge path whereby (1) it neutralizes the electron space charge surrounding the main cathode and causes a very great increase in emission, and (2) it effectively acts as a low impedance conductor connected between the main cathode and the main anode. Because of these effects the load current is very large, e. g. $\frac{1}{2}$ ampere, despite the very low main anode potential, e. g., 5 volts. As a result a load-current multiplication-effect results from the use of the auxiliary discharge. The amount of multiplication depends on the density of the plasma which therefore should not be subject to spurious changes if a large spurious component in the load current is to be avoided.

In one class of plasmatrons the presence of the plasma is intended to influence only the direct current component of the load current and to

5 this end the auxiliary discharge is energized with a steady direct potential and no measures are taken to modulate it. Moreover, the input signal is applied to a load current control grid which is located in the path of the low velocity load current where it will not influence the plasma density. In these tubes it is the fact that a control grid by being so located does not influence the plasma density that enables it to retain control even though it is entirely immersed in plasma. Incidentally, the ability of this grid to control the load current is not based on cooperation with an electron space charge, as in the case of a conventional hard tube, but instead its control is 10 based on the following: the grid, being negatively biased, is surrounded by a sheath of positive ions; as an input signal varies this bias the sheath varies in thickness; and this changes the cross-sectional areas and hence the conductivity of columns of conductive plasma which extend through the grid openings between the main cathode and the main anode. The attainment and retention of this type of load current control in a gas tube marked a great advance. In most 15 other kinds of gas tubes, e. g., thyratrons, continuous control is impossible because the high velocity ionizing discharge occurs over the very same path as that followed by the load current and therefore extends through the grid openings. The reason why this deprives the grid of control is that each variation in its potential varies the plasma density and therefore produces indirect effect on the load current which 20 are opposite to and exactly offset the direct effects which it has thereon. Since plasmatrons have 25 separate load-current and ionizing-discharge paths the load current control grid may be located 30 athwart only the former where it will not influence the plasma and in this way these offsetting 35 indirect effects can be avoided.

In another class of plasmatrons the presence of the plasma is intended to influence the signal component of the load current as well as its direct current component and to this end they are provided with means for signal modulating the plasma density.

40 The limitation referred to above is manifested in both classes of plasmatrons: it being manifested in the first-mentioned class in that the plasma density is not really constant but instead 45 is subject to fluctuations and random variations; and it being manifested in the second-mentioned class in that the signal variations of the plasma density are intermixed with the same kinds of 50 spurious fluctuations and random variations.

2

Any of these tubes in either of these classes can be considered as comprising a group of electrodes for carrying the load current and a gas diode for generating the plasma. The source of electrons for the diode is the auxiliary cathode and its anode, or collector of electrons, is either an electrode especially provided for this purpose or one of the electrodes of the load current circuit, e. g., the main cathode, or a group of those electrodes serving as a composite anode. In any case the operation of the auxiliary discharge is substantially the same as that of an ordinary gas diode. At the instant when a gas diode fires its electron space discharge becomes abruptly augmented by a very large conduction current. There is a short interval in which a regenerative increase in current takes place and the diode tends to "run away." During this interval the greatly increasing electron flow greatly increases the generation of plasma which in turn further increases the electron flow, and so forth. Excluding the academic possibility that the external energizing circuit has zero series impedance, the large current inevitably will cause enough of an IR drop in it to tend to extinguish the discharge. However, the plasma decays rather slowly so that a large current and therefore the drop in the applied potential persists for a very sensible period of time. When this period has passed the applied potential will be restored and the next regenerative interval, i. e., a fresh cycle, will commence. Thus a gas diode connected to a source of energizing potential is inherently a relaxation oscillator. As a result the discharge current, and with it the plasma density, is inherently subject to gross periodic fluctuations. These are sometimes referred to as plasma oscillations. In a plasmatron the plasma density fluctuations effect very substantial fluctuations in the output current.

In addition there are other variations which are more random in their nature. They are probably attributable to the random distribution of the velocities and directions-of-emission of the thermal electrons provided by the auxiliary cathode as those random phenomena are translated into the generation of ions and probably the average recurrence rate of the random gas fluctuations is probably related to the average recurrence rate of the thermal noise impulses by some factor which depends on the average number of ionizing collisions and therefore on the magnitude of the arc-drop. Thus gas discharge random noise is often "coarser" than the thermal noise encountered in hard tubes.

It is therefore an object of the present invention to reduce the generation of noise in gas diodes generally as well as in the types of tubes described above each of which inherently includes a gas diode as a source of plasma.

It is a further object of this invention to reduce both the fluctuation noise and the random gas discharge noise of a gas tube.

In general the objects of the present invention are attained by providing, either within a gas diode or plasmatron or external thereto in the circuit for energizing a gaseous discharge therewithin, a constant current means for so limiting the discharge current that the relaxation-oscillation phenomenon is either markedly reduced or eliminated and that the sustaining potential for the gaseous discharge device will have a value which is adverse to the generation of coarse random gas noise.

In the drawing: Figure 1 is a longitudinal sec-

tional view of an illustrative embodiment of a tube according to the present invention, the section is taken along lines 1-1 of Figure 2 and in a plane which is parallel to the axes of the cylindrical cathodes;

Figure 2 represents another longitudinal sectional view of this embodiment, this section being taken along the line 2-2 of Figure 1 in a plane perpendicular to that of the section of Figure 1;

Figure 3 is a longitudinal sectional view of a modification of my invention, the section being taken like that of Figure 2;

Figure 4 is a longitudinal sectional view of another modification, the section being taken as in Figures 2 and 3;

Figures 5, 6 and 7 are schematic circuit diagrams of amplifier circuits respectively using the tubes of Figures 1 and 2, 3, and 4, and

Figure 8 is a schematic circuit diagram of a rectifier circuit using a gas diode improved according to the present invention.

The gas tube 10 shown in Figures 1 and 2 comprises a gas tight envelope 11 which in this illustrative embodiment is of substantially rectangular shape. The load current in this tube originates from a main indirectly heated cathode 12 and is received at a main anode 13. An auxiliary indirectly heated cathode 14 serves as a source of electrons for the ionizing discharge. A load current control grid 15 is mounted intermediate the main cathode and anode. A fine mesh screen 16 is mounted between the auxiliary cathode 14 and the group of load current electrodes 12, 13 and 15. Preferably the screen 16 should be of very fine mesh, for example, with openings which are of the same order as the mean free path of a positive ion and preferably the screen should completely separate the space within the envelope which contains the auxiliary cathode 14 from that containing all of the load current electrodes. In the particular embodiment shown herein the screen 16 is mounted within a rectangular frame 17 which is closely fitted to the inside surface of the envelope 11. However this exact arrangement is not necessary. Instead the frame 17 could be smaller than the cross-sectional area of the envelope 11 and in the form of a cage entirely surrounding the auxiliary cathode; or it could be in the form of a solid, i. e., non-foraminous, partition with the fine mesh screen covering only a relatively small central opening. The main and auxiliary cathodes 12 and 14 are supported respectively on rods 18 and 19 which extend through the top of the envelope 11 to serve as terminal pins over which the sleeves of the cathodes can be polarized. Respectively associated with these cathodes, there are two additional terminal pins 20 and 21 which serve for completing the connection of the heaters of these cathodes to sources of current. As shown in the drawing each of the cathodes 12, 14 has an internal heater, 22, 23 respectively, which is connected on one of its ends to the cathode sleeve and on its other to the terminal pin associated with that cathode. A terminal pin 24 extends through the bottom of the envelope 11 to the frame 17 to provide a means for connecting the screen 16 to an external circuit. A similar pin 25 extends through the bottom of the envelope 11 to the control grid 15. Because of the large size of the control grid 15 shown herein by way of example, a pair of rods 26 are employed to assist the terminal pins 25 in supporting the grid. Likewise the horseshoe shaped main anode 13 is carried on a terminal pin 27 and a pair of support rods 28.

Tube 10 may be processed in any number of ways well known in the art to provide a gaseous filling (G) within its envelope prior to sealing off. Any suitable gas or mixture of gases may be utilized. The gas pressure for any particular embodiment will be in accordance with its specific electrode geometry and spacings and must be such to favor the formation of a self sustaining ionizing discharge. A number of plasmatron tubes have been found to operate satisfactorily with a filling of helium of a pressure of approximately 750 microns. However, as is well known other gases and other pressures may be used, e. g., pressures which lie within the range of between approximately 100 microns and several 15 millimeters of mercury.

Figure 5 shows a circuit in which the embodiment of Figures 1 and 2 may be employed according to the present invention. In this figure four direct potential sources are shown, a low-potential load-current-energizing source 30; a high potential auxiliary-discharge-energizing source 31; a heater current source 33 for the auxiliary cathode 14; and a biasing-source 32 for the main control grid 15. The source 30 is used for maintaining the small non-ionizing potential difference between the main cathode 12 and the main anode 13. It may consist of a number of storage battery, or any similar fairly-high-current, low-voltage source. This is because of the fact that although it must not provide much voltage it must be capable of delivering to a utilization device through the tube 10 a very substantial signal-bearing current, i. e., a current 35 which may easily have an average value of the order of one to several amperes. Conversely the source 31 should be capable of providing a relatively much higher potential but need not be capable of providing a particularly large continuous average current. This is because it serves to energize the efficient, low-current ionizing-discharge. The source 33 is merely a heater current supply. Finally the source 32 is only called upon to provide a low voltage and that with little current since it merely provides a small negative bias between the control grid 15 and the auxiliary cathode 14. In the circuit of Figure 5 the main cathode is at the direct potential of ground and the main anode is nearly so since the source 30 establishes only a small voltage difference between these elements. As to alternating currents they are both grounded since the source 30 may be assumed to have a low internal alternating current impedance whether it is a battery with or without a by-pass condenser or an equivalent low voltage power supply. Connected in series with the source 30, the main cathode 12 and the main anode 13 there is the primary of an output transformer 34 coupling the varying component 60 of the output current of tube 10 to a loud speaker 36. In this arrangement the main anode 13, the control grid 15, and main cathode 12 serve together as a composite anode for attracting and receiving electrons from the auxiliary cathode 14 to establish the auxiliary discharge. Accordingly, the source 31 is connected between the auxiliary cathode 14 and ground, i. e., the voltage reference for the composite anode, in such polarity that the auxiliary cathode is sufficiently 70 negative with respect thereto to produce the required ionizing discharge. A resistor 37 is shown in series with the source 31 and the auxiliary-cathode 14 where such a resistor is usually employed for limiting the current drawn by the

tube due to its tendency to "run away." Since the principal feature of the present invention involves limiting the auxiliary current by the use of a constant current means either inside of the tube 10 or in its auxiliary discharge energizing circuit, the resistor 37 may be dispensed with.

As pointed out above, in previous plasmatrons the current passing between the auxiliary cathode 14 and the composite anode 12, 13, 15 has been subject to current fluctuations. Figure 5 shows two ways of suppressing these fluctuations. The first is to adjust the temperature of the auxiliary cathode 14 so that for the particular operating potentials applied to the tube 10 its emission is temperature limited. To this end the heater circuit connecting the source 33 to the cathode 14 includes a potentiometer 38. When the use of temperature limited emission is relied on to avoid fluctuations in the ionizing discharge, this will in itself suffice and therefore it will be possible to dispense with the use of the screen 16 or to polarize it at a sufficiently high potential to draw away from the auxiliary cathode 14 all of that limited emission which it does provide. However, a second and preferred way of suppressing the fluctuations relies on including a screen 16 in the tube 10 and using it in such a way that the ionizing current is limited without the use of temperature limited emission. In doing this the auxiliary cathode may be heated to a temperature near that at which it will be operated in a conventional grid controlled hard tube amplifier, i. e., to a high enough temperature to emit copiously. At the same time the screen 16 is adjusted to a positive potential of some small magnitude such as 5-10 volts which provides so low a field gradient between itself and the cathode that space charge limitation will set in. Under such conditions a limited current of 40 electrons will be attracted toward the screen 16 and a portion of this, also limited and constant, will pass through its openings toward the composite anode 12, 13, 15. In effect the cathode 14 and the screen 16 when operating together in this 45 way constitutes the equivalent of a virtual temperature limited cathode. When the potential provided by the source 31 is sufficient to accelerate the limited current of electrons to the composite anode at high enough speeds to cause 50 a breakdown and to maintain a going arc, the auxiliary discharge circuit will be functioning in the manner required to provide plasma in the tube 10. The potential on screen 16 can be adjusted downward to increase the arc drop until a 55 very efficient high voltage low current arc is established. In such an auxiliary discharge each electron on the average will have a relatively large number of ionizing collisions. This certainly increases the ionizing efficiency and it seems in addition to cause the random noise impulses to occur with an increased average repetition rate. This change in the random noise may be preferred for certain purposes as offering less interference in frequency bands usually occupied 60 by intelligence signals, e. g., the audio band.

When the screen 16 is properly adjusted the fluctuation noise can be reduced as much as 90%. This is due to the fact that the tendency of the limited ionizing current to remain constant will not be disturbed by the sudden generation of highly conductive plasma in the space to the right of screen 16 and that it cannot be disturbed due to the auxiliary cathode's becoming bathed in plasma and thereby having its space charge neutralized. While some diffusion of positive ions through the fine openings of the screen 16 and

towards the auxiliary cathode can occur, the rate of this diffusion can be made very low with respect to the rate at which they will recombine with free electrons (in the region to the left of the screen) if the openings are very small. An incidental advantage resulting from the use of the screen 16 is that back bombardment of the auxiliary cathode by positive ions is almost entirely eliminated.

In Figure 5 an arrangement is shown at 39 whereby it is possible to adjust the potential of the screen 16. In addition, a conventional type of signal input circuit is shown at 40 for superimposing signal modulations on the bias of the load current control grid 15. If desired the same signal may be applied to the screen 16 instead of the grid 15 by substituting the circuit represented in dotted lines at 41 for the circuit 49. Or, where a dual input device is needed, both circuits may be used.

Many of the elements comprising the embodiment of Figure 3 correspond to above-described elements comprising that of Figure 1 and they are designated by the same reference numerals. However, in this embodiment an auxiliary-discharge control grid 29 is placed in cooperative relationship between the auxiliary cathode 14 and the screen 16 and the load current control grid 15 is eliminated. In such an embodiment the electrodes providing the auxiliary discharge, i. e., the cathode 14, the grid 29, and the screen 16 and those comprising the composite auxiliary anode together constitute an arrangement very much like a tetrode. In this type of tube the load current is controlled indirectly by modulating the plasma density.

Figure 6 shows a circuit for utilizing the tube of Figure 3. This circuit contains many elements like elements of the Figure 5 circuit and these bear the same reference numerals. However, in this circuit it is the control grid 29 which is provided with a signal input circuit (43) and a biasing arrangement (42) whereas in Figure 5 the corresponding circuit portions 32 and 40 are provided for the grid 15. If desired an embodiment may be made which includes both a load current control grid 15 and an auxiliary-discharge control grid 29 to afford a dual input device. In such a case an appropriate circuit would include the circuit portions 32 and 40 as well as those shown at 43 and 42.

The embodiment of Figure 4 comprises a plasmatron of the kind described in copending application, Ser. No. 217,912, now U. S. Patent No. 2,611,884. In this kind of plasmatron the ionizing discharge is formed into a directed stream having a constricted portion of smaller cross-sectional area than the rest of the stream and a means is provided for constriction-modulating the ionizing stream to vary the plasma density and thereby the load current. In this Figure 4 embodiment a number of the tube elements are like the elements used in the embodiment of Figures 1 and 2 and that of Figure 3 and therefore they bear the same reference numerals. In Figure 4, however, the load current control means comprises a beam-forming slotted shield 50 and a constriction modulating electrode 51. The electrode 51 has a slot 52 which is aligned with the slot (53) of the shield 50. For a complete explanation of the constriction-modulating principle of operation, reference is made to the above-mentioned copending application. In Figure 4 the required fine mesh screen has the form of a cage 54 which surrounds the auxiliary cathode 14. It is operated

in the manner above described for the screens 16 to provide a constant auxiliary current.

Figure 7 shows a circuit as for utilizing the tube of Figure 4. In this circuit it is the constriction modulating electrode 51 to which the input signal is applied and accordingly there is a circuit portion consisting of biasing means 55 and an input means 56 to take the place of corresponding circuit portions shown in the circuits of Figures 5 and 6. In the operation of the circuit of Figure 7 the electrode 51, being negatively biased, collects and becomes surrounded by a sheath of positive ions. As a result variations in the direct potential bias of this electrode are effective to vary the thickness of this sheath and thus to modulate the constriction in the ionizing stream. These constriction-modulations will vary the arc drop and hence the plasma density, and as a result they will modulate the load current. However, the useful signal variations in the plasma density will not be accompanied by the usual plasma fluctuations. In each of the circuits in Figures 5, 6, and 7 there is shown a block L which is intended to represent an external current limiting means which may be used in addition to the current limiting means already described or in place thereof. An example of a suitable external current limiting means would be a pentode tube with its plate and cathode connected in series with the source 31 and the auxiliary cathode 14.

Each of the tubes shown herein in effect comprises as a subcombination a gas diode which serves to generate plasma and is modified to reduce its generation of spurious noise. Such a gas diode has great possibilities for usefulness without being used in a plasmatron, for example, it may be used as a rectifier. The circuit of Figure 8 represents a rectifier circuit which employs such a diode and may be suitable, for example, for changing a 110 volt alternating current voltage into a direct potential of perhaps 300-400 volts. The circuit comprises a gas diode 60 having an indirectly heated cathode 61, anode 62, and a fine mesh screen 63 positioned in the tube between these elements to function like the screens 16 and 54 described above. A transformer 64, which serves to step up the peak-to-peak value of the alternating voltage to a value which is large enough for the desired D. C. voltage, has its secondary 65 connected between the cathode 61 and the anode 62. The screen 63 is connected to a tap of the secondary 65 so that during the half cycle when the rectifier 60 conducts the instantaneous potential of the screen will be within a small range of positive values, with respect to the cathode 61, which are suitable for keeping the current space charge limited and free of spurious fluctuations. Of course, if desired, a D. C. bias can be provided between the screen 63 and the cathode 61. Each pulse of current drawn through the gas tube 60 will produce a voltage drop across a resistor 66 and a filter 67 will act in a known manner to derive the D. C. component of this voltage and to supply a stored source of direct potential in the reactive elements of the filter.

The screen 16 does not necessarily have to completely isolate from the rest of the inside of envelope 11, the portion thereof which contains the auxiliary cathode. If there were an open space all around the perimeter of the screen 16 between it and the adjacent inside surfaces of the envelope it would still easily perform its desired function of electrically shielding the

auxiliary cathode and it might also perform its additional function of keeping positive ions from reaching that cathode provided the ions would have long paths to reach the cathode around the shield that they would be neutralized on the way. In fact, means could be positioned along the way for the purpose of trapping the ions in while en route, e. g., a negatively polarized frame-shaped member extending around the periphery of the screen to establish a low-potential trough. 10

What is claimed is:

1. A gas amplifier tube comprising: a sealed envelope containing a gaseous filling; means for providing a load current through the tube comprising a main cathode and a main anode in cooperative spaced relationship; means including an auxiliary cathode for producing a current-stabilized ionizing discharge to provide a conductive plasma between said main cathode and anode; means adjacent said auxiliary cathode for forming the ionizing discharge into a directed stream having a constricted portion of smaller cross-sectional area than the rest of said stream, and means for constricting-modulating said stream to thereby modulate the plasma density. 20

2. A gas tube as in claim 1 in which the means for forming the ionizing discharge into a stream comprises a slotted shield, between the auxiliary cathode and said means for carrying a load current, with its slot in alignment with the path along which said stream is to be directed, and said means for producing an ionizing discharge includes a fine mesh screen between said auxiliary cathode and said slot.

3. A gas tube as in claim 2 in which said constricting-modulating means comprises a slotted electrode having a small total area as compared to said shield and positioned with its slot in substantial registry with that of the shield.

4. A gas amplifier tube comprising: a sealed envelope containing a gaseous filling; means for carrying a load current through the tube comprising a main cathode and a main anode in cooperative spaced relationship; means including an auxiliary cathode for producing a current-stabilized ionizing discharge to provide a conductive plasma between said main cathode and anode; said second mentioned means including a fine mesh screen between said auxiliary cathode and said first mentioned means; and a control grid between said main cathode and said main anode. 50

5. A gas amplifier tube comprising: a sealed envelope containing a gaseous filling; means for carrying a load current through the tube comprising a main cathode and a main anode in cooperative spaced relationship; means including an auxiliary cathode for producing a current-stabilized ionizing discharge to provide a conductive plasma between said main cathode and said anode; and an auxiliary discharge control grid adjacent said auxiliary cathode. 60

6. A tube as in claim 5 and further comprising a control grid between said main cathode and said main anode.

7. A gas amplifier tube comprising: a sealed envelope containing a gaseous filling; means for carrying a load current through the tube comprising a main cathode and a main anode in cooperative spaced relationship means; including an auxiliary cathode for producing a current-stabilized ionizing discharge to provide a con-

ductive plasma between said main cathode and said anode; said second-mentioned means including a fine mesh screen between said auxiliary cathode and said first-mentioned means; and an auxiliary discharge control grid adjacent said auxiliary cathode and between said auxiliary cathode and said screen.

8. A gas amplifier tube comprising: a sealed envelope containing a gaseous filling; means for carrying a load current through the tube comprising a main cathode and a main anode in cooperative spaced relationship, and means including a temperature-limited cathode for producing an ionizing discharge to provide a conductive plasma between said main cathode and anode.

9. A gas tube comprising: a sealed envelope containing a gaseous filling; a group of load circuit electrodes within the envelope and including at least one main cathode and a main anode having, respectively, electron emitting and electron receiving surfaces which define opposite ends of a predetermined load current path; means including an auxiliary cathode for producing an ionizing discharge of electrons along a path within in said envelope which does not coincide for all of its length with all of said load current path but includes a portion in such close proximity thereto, for example, coincident therewith or crosswise or adjacent thereto, that said ionizing discharge bathes the main cathode and extends over all of said current path; said last-mentioned means including an electron-transparent electrode between said auxiliary cathode and said group of load circuit electrodes for controlling an electric field adjacent the cathode to attain space charge limitation of its emission.

10. A tube as in claim 9 further comprising an auxiliary discharge control grid between said auxiliary cathode and said transparent electrode.

11. A gas tube as in claim 9 and including a control grid positioned athwart said load current path.

12. A gas amplifier tube comprising: a sealed envelope containing a gaseous filling; means for carrying a load current thru the tube comprising a main cathode and a main anode in cooperative spaced relationship; means including an auxiliary cathode and a fine mesh screen adjacent it for producing a space charge limited current of ionizing electrons to provide a conductive plasma between said main cathode and main anode; means between said auxiliary cathode and said first-mentioned means for forming the ionizing current into a directed stream including a constricted portion; and means for constricting-modulating said stream to thereby modulate the plasma density.
